WINDOW SASH HOLDER AND LOCK

Claude E. Axtell, Weed, Calif.

Application May 26, 1938, Serial No. 210,227

2 Claims. (Cl. 292—15)

This invention relates to devices used in connection with window sashes for holding the sash in a raised position, and in accordance with the present invention improved means is provided both for holding the sash in raised position and also for locking the sash securely at the desired position of adjustment.

The invention consists in the provision of means for holding the upper and lower sashes at the desired position of adjustment and for releasing the sashes simultaneously so that either or both may be raised or lowered as found desirable.

The invention together with its objects and advantages will be understood from a study of the following description taken in connection with the accompanying drawings wherein:

Figure 1 is an enlarged detail sectional view through a portion of a window frame and upper and lower sashes illustrating the application of the invention, and

Figure 2 is a view taken substantially at right angles to Figure 1 and further illustrating the invention.

Referring to the drawings by reference numerals it will be seen that 5 indicates a side rail of a lower sash and 6 indicates the side rail of an upper sash.

In accordance with the present invention each of the rails 5 and 6 is provided in the outer edge thereof with a longitudinal groove 7 in which is secured through the medium of screws or other fastening elements 8 a rack bar 9.

Each rack bar 9 is corrugated transversely thereby forming alternate concave and convex portions 10 and 11 respectively.

Also for each sash, and cooperating with the rack bar 9 provided therefor, is a catch assembly which, in the present instance, consists of a mounting plate 12 secured to the window frame 13 through the medium of screws or other fastening elements 14 and disposed opposite a slot 15 provided in the frame.

In connection with the above it will be understood that the mounting plate 12 forming part of the catch assembly provided for the lower sash, is mounted on the frame 13 at one side of the parting strip with which the frame is usually equipped, while the mounting plate 12 for the catch assembly provided for the upper sash 6 is mounted on the frame 13 at the opposite side of the parting strip (not shown).

Each mounting plate 12 has extending inwardly therefrom through the slot 15 a pair of bracket arms 16 between which is pivoted as at 17 an

intermediate portion of a lever 18 that is somewhat sinuous in side elevation as shown in Figure 1.

Furthermore the lever 18 as shown in Figure 2 is substantially U-shaped, and rotatably supported between the sides of the lever at the open end of the U is a roller 19 that serves as a catch or detent and is normally urged outwardly through a slot 20 provided therefor in the mounting plate 12 to engage the corrugated surface of the rack 9 through the medium of a coil spring 21. Coil spring 21 has one end disposed against the inner side of the mounting plate 12 and an opposite end suitably connected with and bearing against the free end of the lever 18.

In connection with the above it will be noted that the lever 18 forming part of the catch assembly for the lower sash is disposed downwardly while the lever 18 forming part of the catch assembly for the upper sash is disposed upwardly as clearly shown in Figure 1.

Further in accordance with the present invention the mounting plate 12 of each assembly has pivoted to the inner side thereof as at 22 a latch bar 23 that has the free end thereof extending between the sides of a lever 18 and at said end is provided with a suitably shaped notch 24 with which is cooperable a keeper pin 25 bridging the space between the sides of the lever 18. The latch bar 23 is normally urged in a direction to engage notch 24 thereof with pin 25 whereby to secure the lever 18 against rocking movement on its pivot 17 through the medium of a coil spring 26 which at one end is suitably connected with the latch bar 23 and at its opposite end is suitably anchored to one of the bracket arms 16.

It will thus be seen that with the notch 24 of the latch bar 23 engaged with the pin 25 lever 18 will be held against rocking movement and consequently the detent roller 19 engaging in a concave portion 10 of the rack bar will serve to secure the window sash against being raised or lowered as the case may be.

Further in accordance with the present invention means is provided whereby the levers 18 may be simultaneously locked or released as desired. To this end there is provided a substantially S-shaped locking bar 27 which intermediate its ends is pivoted as at 28 within a slot 29 provided therefor in an internal partition 30 within the window frame 13 as shown in Figure 2. One end 27a of the locking bar 27 extends downwardly at one side of the partition 30 and has a beveled terminal 31 engageable with a beveled lug 32 on the free end of the latch bar 23.

of the lower sash rail latch assembly while the other arm 27b of the locking bar 27 extends upwardly at the opposite side of the partition 30 and is provided with a beveled terminal 33 that 5 is engageable with a complementarily beveled lug 34 provided on the free end of the latch bar 23 forming part of the upper sash latch assembly. It will thus be seen that when the terminals 31, 33 are engageable with the lugs 32, 34 as shown 10 in Figure 2, latch bars 23 against the action of springs 26 are urged to a position disengaging notches 24 and pins 25 thus permitting the levers 18 to swing freely on their pivots 17 to the end that the sashes 5 and 6 may be raised or lowered 15 5 as found desirable. When however the locking bar 27 is rocked, in a manner hereinafter made manifest, to disengage the terminals 31, 33 from the lugs 32, 34 latch bars 23 in response to the action of springs 26 will swing in a direction to 20 engage the notches 24 thereof with the pins 25 thereby locking the levers 18 against swinging movement on their pivots 17 and thereby secure the window sashes 5 and 6 against being raised or lowered, and consequently in the desired position 25 of adjustment.

From operating the lock bar 27 there are provided push buttons 35, 36 that are slidably supported by a plate 37 suitably mounted on the inner sides of the window frame 13 and secured 30 thereto through the medium of screws or other fastening elements 38. Plate 37 has extending therefrom and through a slot 39 provided therefor in said face or side of the frame 13 a pair of lugs or ears 40 between which is pivoted as at 41 35 a lever 42. Lever 42 is pivoted to the inner ends of the push buttons 35, 36 as at 43 and 44, respectively, and intermediate its ends lever 42 is pivoted as at 45 to an extension 46 provided on the bar 27 intermediate the ends of the bar.

40 A spring 47 is suitably anchored at one end to one of the ears 40 and at an opposite end is connected with the pivot 45 and serves to hold the lever 42 and associated parts in the position to which it is swung incidental to an inward movement of either of the push buttons 35, 36.

In Figure 2 the parts are shown in the position occupied when the sashes are unlocked. Obviously to lock the sashes the operator pushes inwardly on the button 35 causing the lever 42 to 50 swing about its pivot for projecting the button 36 and at the same time to swing the locking bar 27 on its pivot 28 and in a direction to move the terminals of the arms of the bar 27 out of engagement with the latch bars 23 permitting the bars 55 23 to swing in response to the action of springs 26 in a direction to engage the notches 24 thereof with the pins 25 and thereby secure the levers 18 against swinging movement and consequently the sashes 5 and 6 in locked position.

60 When it is desired to unlock the sashes the

operator then pushes inwardly on the push button 36 thus returning the parts to the position shown in Figure 2, and in which position, with the terminals of the arms 27a, 27b of lock bar 27 engaging the latch bars 23 the latter are moved 5 against the action of springs 26 to disengage the notches 24 from the pins 25 thus leaving the levers 18 free to swing on their pivots 17 and consequently permitting the sashes 5 and 6 to be raised or lowered as found desirable. 10

It is thought that a clear understanding of the construction utility and advantages of an invention of this character will be had without a more detailed description.

Having thus described the invention what is 15 claimed as new is:

1. In a window holder and lock, and in combination with a window frame, detents mounted on the frame one for a lower window sash, and the other for an upper window sash, and each of said 20 detents including a pivoted lever provided with a keeper pin, a spring-biased latch bar for each lever having a free end provided with a notch to engage said keeper pin whereby to lock the lever against swinging movement, a locking bar pivotally mounted intermediate its ends interiorly of the window frame and having one end arranged to engage the latch bar of one detent and a second end arranged to engage the latch bar of the other detent whereby to move said latch bars simultaneously out of engagement with the keeper pins, and manual means operable exteriorly of the frame for swinging the lock bar into and out of engagement with the latch bars. 25

2. In a window holder and lock, and in combination with a window frame, detents mounted on the frame one for a lower window sash, and the other for an upper window sash, and each of said 30 detents including a pivoted lever provided with a keeper pin, a spring-biased latch bar for each lever having a free end provided with a notch to engage said keeper pin whereby to lock the lever against swinging movement, a locking bar pivotally mounted intermediate its ends interiorly of the window frame and having one end arranged to engage the latch bar of one detent and a second end arranged to engage the latch bar of the other detent whereby to move said latch bars simultaneously out of engagement with the keeper pins, a pair of push buttons operable 35 from one side of said frame and slidably mounted on the frame, link means operatively connecting said push buttons with the locking bar for transmitting movement of a push button to the locking bar to swing the latter in a desired direction, and a spring device associated with said link means and acting to yieldably retain the lock bar in the position to which it moves in response to an inward movement of a push button. 40
